UNITED STATES PATENT OFFICE.

JOHN EDMUND MARSHALL, OF SANDIACRE, ENGLAND.

SPRING-MATTRESS AND SPRING SEATING-SURFACE.

1,102,280.

Specification of Letters Patent.

Patented July 7, 1914.

Application filed October 27, 1913. Serial No. 797,630.

To all whom it may concern:

Be it known that I, JOHN EDMUND MARSHALL, a subject of the King of Great Britain, and a resident of Sandiacre, Derbyshire, in England, have invented a certain new and useful Improvement in or Relating to Spring-Mattresses and Spring Seating-Surfaces, of which the following is a specification.

10 This invention relates to spring mattresses, the seating surfaces of railway carriages, motor buses, motor cars, and the like, and refers to improved means for connecting together the respective springs comprising a mattress or seating surface.

15 The invention is applicable to mattresses or seating surfaces which are built up of a series of vertical springs connected to each other, said springs being if required, say in 20 the case of seating surfaces, inclosed by upper and lower external wire frames, which constitute the stuffing edges.

25 Referring to the drawings, Figure 1. is a sectional elevation, and Fig. 2. a plan showing part of a spring seating surface constructed according to my invention.

Like letters indicate like parts throughout the drawings.

30 The present invention refers to mattresses or seating surfaces, which are built up of a series of vertical springs set close together and connected to each other throughout their full length. This construction has hitherto been effected by interlacing the 35 respective coils of each of the springs, with the corresponding coils of the contiguous springs.

According to the present invention, the 40 springs comprising a mattress or seating surface such as described, are secured to each other by connecting the coils of each spring to the coils of the contiguous springs, by means of a length of leather, tape braid, or like flexible material, which not only 45 serves to secure the springs together, but is disposed so as to prevent the coils from coming into contact with and rubbing against each other.

As shown in the drawings, a length of 50 flexible material B starting say from the

bottom, is interlaced or carried through the coil of first one spring A and then the other, until the top is reached, and after being passed around the upper coils of both springs A, it is returned to the starting 55 point. In returning, the material B is as shown carried around the first part which is interlaced with the coils, between each of the latter, and after being carried around the lower coils, the two ends of the mate- 60 rial are secured together.

The length of flexible connecting material B when arranged as described, forms a non-metallic buffer between each and all the spring coils, and thus prevents them 65 from rubbing together and making the noise which is inseparable from such action. The whole of the springs A are further effectively and flexibly secured together throughout their length, forming a compact mass, 70 but the connection is of such a nature that local pressure is not extended over a wide area, and the surrounding springs are not therefore pulled over toward those depressed.

75 The external frames D and E which constitute the upper and lower stuffing edges, may be connected to the upper and lower coils of the marginal springs A in the usual manner, that is, by lacing or connecting the 80 said coils to the frames D and E in the usual manner.

What I claim as my invention and desire to cover by Letters Patent is:—

1. A spring seating surface built up of a 85 series of vertical springs secured together by connecting the coils of each of the springs to the coils of the contiguous springs by means of a length of flexible non-metallic material engaging alternately with the coils 90 of both springs, substantially as described.

2. A spring seating surface, comprising a series of helical springs arranged side by side, and stretches of flexible material connecting the adjacent portions of the said 95 springs and extending longitudinally of the springs between their coils.

3. A spring seating surface built up of a series of vertical springs secured together by connecting the coils of each of the springs 100

2

to the coils of the contiguous springs by means of a length of flexible non-metallic material which is first interlaced with the coils of both springs then returned and carried around itself between the coils and the two ends secured together substantially as described.

In testimony whereof I have signed my name to this specification in the presence of two subscribing witnesses.

JOHN EDMUND MARSHALL.
